PIANO ACTION

Francis C. Socin, St. Charles Township, Kane County, Ill., assignor to The Rudolph Wurlitzer Company, Chicago, Ill., a corporation

Application June 20, 1945, Serial No. 600,522

7 Claims. (Cl. 84—239)

1

This invention relates to a piano action, and particularly a compact, so-called compressed grand piano action.

One purpose of the invention is to provide an action adapted for use in a square piano wherein it may be fitted to the front portion of the piano ahead of the sounding board with a minimum of over all depth in a piano of this type. However, features of the invention hereafter referred to may be similarly embodied in actions applicable to other types of pianos.

One feature of the invention resides in a double-acting spring associated with and acting upon both the wippen and the jack. This double-acting spring is so formed and arranged as to exert tension in two directions, exerting downward spring pressure on the wippen and laterally-directed spring tension on the jack to simultaneously and through the same spring action tend to return them to rest position after actuation. By means of such double-acting spring the repetition qualities of the piano are improved, due to the rapidity with which the spring causes the wippen and jack to resume their rest positions.

Another feature of the invention resides in an improved flexible jack having a pivotal link connection between the wippen and hammer. To assure positive action and the desired repetition, a shoulder is provided on the jack member to limit its movement in one direction and provide a cushioned seat when in striking position, while permitting flexing to hammer let-off position.

A still further feature of the invention resides in the provision of an adjustable flange formed of a looped metal strap adapted to be secured to the action rail to provide a hinged support and connection for an operating part, such as the wippen. Wherein the angular relation between the hammer lever and wippen relative to the action rails may vary in accordance with the relation of the keys to the strings, such variation and angular relation may be readily effected by bending or twisting the metal flange. In this manner, the looped bearing end of the metal flange for receiving the hinge pin may be bent out of alignment with the rail to provide a hinge support at any desired angle.

Another feature of this invention resides in the character of the action brackets which support the action rails. In a compressed grand or square piano it is necessary that the action rails extend at different angles to the key-board, and therefore require angularly displaced supporting brackets. It has accordingly been found desir-

2

able to construct the action brackets of metal which is bendable to shape so that one form of bracket may be bent to the desired angle and thereby eliminate the necessity of providing a plurality of brackets of different shape.

The full nature of the invention will be understood from the accompanying drawing and the following description and claims:

Fig. 1 is a side elevation showing one unit of 10 the action in rest position, the supporting rails and parts of the piano structure being shown in section.

Fig. 2 is the same as Fig. 1 showing a portion 15 of the action in striking or actuated position.

Fig. 3 is a diagrammatic illustration of a part 20 of a piano structure showing the angular relation of the action units relative to the action rails.

Fig. 4 is a plan view of a portion of the action 25 rail and its pivotally supported member extending at an angle thereto.

Fig. 5 is a section through the action rail showing 30 an end view of a twisted flange.

Fig. 6 is a front elevation of a flange and supported member with a portion thereof broken 35 away.

In the drawings there is shown, for the purpose of illustrating one application of the invention, a piano structure having a key bed 10, a key board 11, and piano keys 12 pivotally supported on the said key bed in the usual manner. The frame structure of the piano supports a forward pin block 13 supporting the forward portion of the string plate 14, upon which the piano strings 15 are carried. This portion of the structure and pin block is enclosed by a front panel 16. Rearwardly of the action the frame structure supports and includes the post or beam 17. Supported by a series of action brackets 19a, there are action rails 19 and 20. Said brackets 40 are of bendable metal so that they may be bent to extend at such angles as to support the rails in their respective angular relation to the key bed. The action rail 21 is secured to the forward side of the post 17.

Pivotaly mounted on the flange 20a carried by the action rail 20 there is a hammer lever 22 extending rearwardly and downwardly therefrom to rest upon the action rail 19 when in rest position. Said hammer lever carries the hammer 23 in position to strike the piano string 15.

Pivotaly supported by the action rail 19 through an angularly adjustable flange 24 there is a wippen 25 extending substantially horizontally and forwardly from said rail in position to

be engaged and actuated by the capstan screw 26 carried on the rear end portion of the key 12.

The free or actuating end of the wippen carries a flexible jack or fly comprising the jack member 27 and link member 28. The lower end of the jack member is pivotally connected with the free end of the wippen, the upper end thereof being pivotally connected through the link member with the hammer lever 22. The end of the jack member pivoted to the wippen is provided with a let-off head 29 engageable with the regulating button 30 adjustably mounted upon the action rail 20. The opposite end of the jack member 27 is formed or shaped with an upwardly protruding shoulder 31 so formed and shaped as to provide a seat for the link member 28 when the jack is in rest position. Said shoulder is provided with a suitable pad and is adapted to limit the flexing movement of the jack in returning to rest position and maintain the jack members in proper alignment for repeated strokes in transmitting the striking action from the wippen to the hammer.

For providing maximum flexibility and repetition of the action, there is provided a double-acting spring 32. One end of said spring is anchored at 32a to the wippen action rail 19 by a pin or any suitable means, while the other end thereof is hooked into a cord 33 carried by the jack member 27 near the link member 28. Intermediate the ends of the spring it is coiled at 32b to seat in a groove 25a provided in the upper surface of the wippen to bear thereagainst under spring tension. Said spring is so formed and tensioned that the arm portion between the wippen flange and the wippen engaging loop exerts a yielding downward pressure on the wippen to maintain it in contact with the capstan screw and act to rapidly return the wippen to rest position after each stroke. That arm or portion of the spring between the wippen and its connection with the jack is so formed and tensioned by its loop as to exert a yielding force upon the jack, tending to rapidly return it to rest position after each stroke.

The key 12 also carries a back check 34 for the hammer and engages a damper lever 35 at its free end, said lever being pivotally supported at its opposite end by the action rail 21. Said lever is maintained in contact with the key by the spring 36 to hold the damper head 37 in string dampening engagement under normal tension. Said head is connected with the lever through a connecting rod 38.

It will be noted that whereas the flexible jack with its seating shoulder and its associated double-acting spring may be applicable to different types of actions and pianos, herein it is illustrated as applied to a so-called compressed action, particularly suitable for use in a square piano of minimum depth. Thus, it will be noted that the entire action lies in a comparatively small space in front of the sounding board and adjacent the front panel of the piano.

As best illustrated in Figs. 3-6, the flange 24 is formed of a metal strap looped upon itself, the loop forming a bearing for receiving the hinge pin of the wippen 25. The body portion of the flange is bifurcated to receive a screw 40 for securing it to rail 19. The free ends of one strap portion of the flange are bent inwardly at 41 to bite into the rail to securely fix the flange in its adjusted position. The flange is provided with a reduced neck portion 42 to be straddled by the bifurcated end of the wippen, which neck portion 42

is looped to provide an apertured bearing 43 to receive the hinge pin 44. By means of this construction the neck portion 42 may be twisted so that the looped bearing portion 43 will extend at a predetermined angle to the body portion depending on the angle at which the action unit (wippen, hammer, etc.) extends in respect to the action rail. Thus, each flange is twisted to provide an angular hinge support according to the particular unit to which it is applied.

The invention claimed is:

1. A piano action including a hammer positioned to strike a piano string, a hammer lever therefor having a pivotal mounting, a wippen having a pivotal support at one end thereof, a jack interposed between said wippen and hammer lever for transmitting action therebetween, and a double-acting spring connected to said wippen support and jack and bearing against said wippen intermediate its ends, the tension of said spring being such as to return said jack and wippen to rest position after actuation under spring tension.

2. A piano action including a hammer positioned to strike a piano string, a hammer lever therefor having a pivotal mounting, a wippen having a pivotal support at one end thereof, a jack interposed between said wippen and hammer lever for transmitting action therebetween, and a double-acting spring mounted for engagement with said wippen and connected with said jack formed under spring tension to exert a yielding downward pressure upon said wippen and exerting a yielding lateral pressure upon said jack such as to return said jack and wippen to their rest positions after actuation under spring tension.

3. A piano action including a hammer positioned to strike a piano string, a hammer lever therefor having a pivotal mounting, a wippen having a pivotal support at one end thereof, a jack interposed between said wippen and hammer lever for transmitting action therebetween, and a double-acting spring having one end connected to said wippen support and the other end connected with said jack, said spring being formed with a tension loop intermediate its ends seating against said wippen, said spring being tensioned between said wippen support and loop to exert a yielding downward pressure upon said wippen, and being tensioned at said loop to exert a laterally directed yielding force upon said jack, whereby said spring will act to return said jack and wippen to rest position after actuation under spring tension.

4. A piano action including a hammer positioned to strike a piano string, a hammer lever therefor, a pivotal support for said hammer lever, a wippen having a pivotal support at one end thereof a flexible jack connected at opposite ends thereof to said wippen and lever, respectively, for transmitting action therebetween, and a double-acting spring having one end connected with said wippen support and the other end connected with said jack, said spring having an intermediate portion bearing against said wippen to return said wippen and flexed jack to rest position under spring tension after actuation.

5. A piano action including a hammer positioned to strike a piano string, a hammer lever therefor, a pivotal support for said hammer lever, a wippen having a pivotal support at one end thereof, a jack member pivotally connected at one end thereof to said wippen, a link pivotally connecting the opposite end of said jack member to said hammer lever for transmitting action

from said wippen to said lever and flexing at the pivotal connection between said jack member and link member to provide a let-off action for said hammer, and a spring having one end anchored to said wippen support to extend into engagement with said wippen, tending to depress said wippen under spring tension to rest position, said spring being looped intermediate its ends and extending therefrom for connection at its free end with said jack member adjacent its pivotal connection with said link member, said loop portion exerting spring tension upon said jack member, tending to return it to rest position after flexing.

6. A piano action including a hammer positioned to strike a piano string, a hammer lever therefor having a pivotal mounting, a wippen having a pivotal support at one end thereof, a jack interposed between said wippen and hammer lever for transmitting action therebetween, and a double-acting spring support for connection with said wippen and jack, said spring being formed to exert spring tension upon said wippen in one direction and upon said jack in a different direction, tending to return said jack and wippen to their rest positions after actuation.

7. A piano action including a hammer positioned to strike a piano string, a hammer lever therefor, a pivotal support for said hammer lever, a wippen having a pivotal support at one end thereof, a jack member pivotally connected at one end thereof to said wippen, a link pivotally connecting the opposite end of said jack member

to said hammer lever for transmitting action from said wippen to said lever and flexing at the pivotal connection between said jack member and link member, a double-acting spring connected to said wippen support and jack member formed with a loop portion intermediate its ends bearing against said wippen, the tension of said spring being such as to return said jack and wippen to their rest positions under spring tension, and a shoulder formed on said jack member engageable with said link member to limit the relative movement therebetween upon being returned to rest position under tension of said spring, the relation of said shoulder and link being such as to provide a rest to maintain them in hammer actuating position while permitting flexing after actuation.
